United States Patent Office

Des. 189,780
Patented Feb. 21, 1961

189,780

ELECTRODE HOLDER

Masick C. Magarian, P.O. Box 494, Fresno, Calif.

Filed Mar. 16, 1960, Ser. No. 59,763

Term of patent 14 years

(Cl. D26—1)

FIG. 1.

FIG. 2.

FIG. 3.

FIG. 4.

Fig. 1 is a side elevation of an electrode holder, showing my new design. The opposite side of the electrode holder from that shown is the same in appearance as the side shown.

Fig. 2 is a top plan view of the electrode holder.

Fig. 3 is a front elevation of the electrode holder.

Fig. 4 is a rear elevation of the electrode holder.

I claim:

The ornamental design for an electrode holder, as shown and described.
